UNITED STATES PATENT OFFICE

2,329,252

THERMAL RELAY RESET ACTUATOR

Paul M. Christensen, Newington, Conn., assignor
to Colt's Patent Fire Arms Manufacturing
Company, Hartford, Conn., a corporation of
Connecticut

Original application January 4, 1941, Serial No.
373,189. Divided and this application Decem-
ber 24, 1941, Serial No. 424,325

6 Claims. (Cl. 200—122)

This invention relates to improvements in thermal relay reset actuator mechanism for use in electric switches of the electro-magnetic motor starter type and is a division of application Ser. No. 373,189, filed January 4, 1941.

The above noted application is directed to improvements in a thermal relay unit. The thermal relay reset actuator mechanism described in the instant application is primarily for use in connection with resetting thermal relay units such as described in said application Ser. No. 373,189 but its use is not to be restricted only with such units.

In the latter application, the thermal relay unit described therein is provided with movable control means to make the relay either automatically or manually resettable to re-establish an interrupted circuit when normal current conditions again prevail in the circuit. Said circuit includes, in the present illustration and description, a switch of the electro-magnetic motor starter type.

The movable control means of the thermal relay unit described in said application Ser. No. 373,189 also includes a reset member comprising a movable control plunger and the principal object of the present invention is to provide a simple and effective actuator mechanism for operating the reset member on each of a plurality of thermal relay units in unison by simultaneously engaging and moving each of said reset members.

Another object of the invention is to provide thermal relay reset actuator mechanism mounted entirely on a removable cover for a casing which houses the electro-magnetic motor starter whereby, when the cover is removed, the reset actuator mechanism is entirely removed therewith to leave the thermal relay units and their movable reset members comprising the movable control plungers fully exposed for manipulation, for example, to move said movable control plungers from automatically resettable to manually resettable position.

A still further object of the invention is to provide a thermal relay reset actuator mechanism having resilient means whereby should one or more movable control plungers fail to properly move, no damage will be suffered by the thermal relay unit or any of its component parts due to continued manipulation of or pressure on the thermal relay reset actuator mechanism.

Other objects and advantages of the invention will become more apparent and will be set

forth in detail by considering the following specification describing the accompanying drawing.

The accompanying drawing shows the embodiment of the invention which is deemed preferable, but it will be understood that the drawing is intended for illustrative purposes only and is not to be construed as defining or limiting the scope of the invention, the claims forming a part of this specification being relied upon for that purpose.

In the drawing:

Fig. 1 is a front elevational view of an electro-magnetic motor starter having two thermal relay units and a thermal relay reset actuating mechanism, partly broken away, mounted on the casing cover and the casing cover being partly broken away, and one of the thermal relays being shown in section taken on the line 1—1 of Fig. 2.

Fig. 2 is a sectional view taken on the line 2—2 of Fig. 1.

Fig. 3 is a sectional view taken on the line 3—3 of Fig. 1 with the casing cover and part of the thermal relay reset actuator mechanism operating button removed.

Fig. 4 is a sectional view taken on the line 4—4 of Fig. 7 showing the switch in open circuit position and the relay operable as automatically resettable.

Fig. 5 is a sectional view similar to Fig. 4 showing the switch in closed circuit position, and the relay operable as manually resettable.

Fig. 6 is a sectional view similar to Fig. 5 showing the switch in open circuit position and held against closing the circuit by the movable control means.

Fig. 7 is a view taken on the line 7—7 of Fig. 1 and showing the relay arranged to operate as automatically resettable.

Fig. 8 is a sectional view taken on the line 8—8 of Fig. 5.

Fig. 9 is a sectional view similar to Fig. 8 showing the parts in their relative positions of Fig. 6.

Fig. 10 is a detail view showing the switch operating link in plan and the switch lever in section on an enlarged scale.

Referring to the drawing and particularly to Figs. 1 and 2 thereof, the numeral 10 designates a casing in which a unitary electro-magnetic motor starter and thermal relays embodying the present invention is housed. The electro-magnetic motor starter and thermal relays are mounted on a base 11, and the base is secured to the bottom of the casing 10 by suitable means such as screws 12, only one of which is shown in

the drawing. The motor starter includes a stationary insulating contact base 13 which is shown fastened to the base 11 by screws 14 which extend therethrough and engage in screw threaded openings in the base 11.

A frame 15 is stationarily mounted on the base 11 by suitable means, not shown, in spaced relation to the stationary insulating contact base 13, and houses the electro-magnet of the motor starter. The coil 16 of the electro-magnet is shown held against accidental movement in its housing 15 by a removable yoke member 17, which is not shown or described in detail in this application since it is not a part of the present invention. The electro-magnet is adapted to reciprocate an armature 18. To afford easy guided movement to the armature, it is suitably attached to a carrier frame 19, which is not shown nor described in detail in this application, but which is slidably supported in the frame 15. A movable insulating contact carrier 20 is attached to the movable frame 18 for reciprocating movement in the space between the stationary contact base 13 and the fixed frame or electro-magnet housing 15 to bring contacts 21 into bridging relation with respect to contacts 22 on the stationary insulating base 13, when the armature 18 is attracted by the electro-magnet and causes frame 19 and carrier 20 to move. Obviously when the armature is released it drops and causes carrier 20 and contacts 21 to move away from contacts 22.

A push button control station 2 is conveniently mounted on the top of the electro-magnet housing 15 with the "start" and "stop" push buttons exposed through the cover of the casing for manual operation, and suitable connection binding posts 24 are provided for making desired circuit connections.

Figs. 1 and 2 of the drawing show two thermal relays, designated generally by the numeral 25, and embodying the present invention, mounted on the base 11 at opposite sides of the frame 15. The relays are identical in construction but reversed as to position. Only one of the relays will be described, the reason for showing two relays being to illustrate a complete actual magnetic motor starter unit adapted to control different circuits. Each relay body or casing is shown as comprising a relatively thick part or block 26 of molded insulating material, and a plate 27 of molded insulating material. The parts 26 and 27 of the casing 25 are separable upon removal of a screw, not shown, which extends through the plate 27 and engages in a screw threaded opening 28 (Fig. 7) in the block. The opening 28 is located at the bottom of a recess 29 which receives a correspondingly shaped projection on the plate 27 and through which the screw extends. Each casing 25, with the mechanism of the thermal relay switch assembled thereon is positioned on the base 11 with the plate 27 against frame 15 of the magnetic motor starter and with openings 30 in alignment with screw threaded openings in the sides of the frame 15. Screws 31 are then inserted through the openings 30 and threaded into the openings in the frame 15 to hold the relays in their established places as part of the unitary structure of the magnetic motor starter.

The relay casing part 26 is substantially rectangular in form, and has an outwardly extending projection 33 on its top. Two of the top corners, one at each side of the projection 33, are cut away to provide shoulders 34 for reception of stationary electrical contact plates 35 and 36

which receive the binding posts 35' and 36' to electrically connect the relay switch, hereinafter described, to the electro-magnet of the motor starter. The arm of the contact plate 35 which receives the binding post 35' overlies one of the shoulders 34, and the other arm of the contact plate is flatly disposed against the face of the casing part 26 at one end thereof. The plate 36 is similarly mounted on the other shoulder 34, and will be hereinafter described more in detail in connection with the switch mechanism. When the plate 21 is attached to the part 26 the structure of the casing then provides recesses at the cut away corners and shoulders 34 in which the binding posts 35', 36' are located (Fig. 1). The relay casing part 26 is open at its front, and a removable closure plate 37 forms, in conjunction with a transverse partition plate 38 and walls of the casing, a chamber to receive and house an electric resistance unit and a bimetallic thermostatic element.

The construction of the electric resistance unit does not form part of the present invention, and the description of the one illustrated will be general, since various types of electric resistance units can be employed. In the drawing (Figs. 2 and 8), the resistance unit comprises a plate 39 of insulating material supporting a grid 40, the terminals of which are looped around eyelets 41 on the insulating plate 39. The plate 39 overlies and covers a notch in the top of the casing part 26 through which the grid is insertible into and removable from the casing 25. The eyelets 41 engage or rest on the tops of stationary electric contact plates 42 which are secured to the top of the casing by any suitable means. Screws 43 engage threaded openings in the contact plates 42 and the heads of the screws engage the tops of the eyelets 41 through which the screws extend to detachably mount the electric resistance unit in operating position in the relay casing. Binding posts 44 on the stationary contact plates 42 are provided for electrically connecting the resistance unit in electric circuits which the thermal relay and motor starter are to control.

The thermostatic element which operates the switch hereinafter described, comprises a bimetallic plate 45, one end of which is rigidly secured to a bracket 46 in any suitable manner. The bracket 46 is substantially U-shaped, and a screw 47 is threaded through openings in the arms of the bracket for calibrating purposes in properly locating the bimetallic plate 45 relative to the grid 40 in its operative position in casing 25. The bracket has an extension 48 (Fig. 2) which receives screws 49 extending through the casing part 26 to firmly but detachably secure the bracket to the casing and maintain the bimetallic plate, in its normal condition, in properly adjusted relation with respect to the grid 40, so that the bimetallic plate will be deflected to operate the switch, about to be described, to interrupt the circuit when abnormal conditions therein cause the resistance unit to be overheated.

Although the grid 40 is shown in the drawing as being positioned in front of the bimetallic plate 45 in the said casing chamber, this arrangement can be reversed, that is, the bimetallic plate can be positioned in front of the grid because the grid is removable from the top of the casing independently of the bimetallic plate. Of course, under such reversed arrangement the bimetallic plate would be secured to its supporting bracket with its other face confronting the grid to obtain deflection of the plate in the same direction as

illustrated in the drawing to properly operate the switch without changing or altering the structure presently described.

The bimetallic plate 45 has a tongue 50 on its free end, and the tongue extends through a slot 51 in the reduced portion 52 of a slide or link in the nature of a strip of insulating material, to detachably connect the bimetallic plate and slide. Obviously, movement of the bimetallic plate during deflections under thermal conditions to which it is subjected in the relay casing will impart movements to the slide or link. The casing part 26 is provided with channels 53 (Fig. 7) which receive the longitudinal edges of the enlarged portion 54 of the slide or link to support it and guide it during its movements. The reduced portion 52 of the slide or link extends through a slot 55 (Fig. 2) in the partition plate 38 in casing part 26, and this arrangement also assists in supporting and guiding the slide or link.

It will be noted (Figs. 4-9), that a chamber 56 is provided in the rear of casing 25 longitudinally thereacross being formed by walls of the part 26, the partition plate 38, and the casing plate 27, to house the switch mechanism; and the enlarged portion 54 of the slide is located transversely across the chamber 56 to actuate the lever 57 of the quick action switch. The switch lever 57 is preferably formed from a thin strip of metal the central area of which is struck-up to impart rigidity to the strip, the struck-up area or hump being designated by the numeral 58. The provision of the struck-up area 58 also stabilizes the lever during its working movements. The area 58 is located, as shown best in Fig. 10, through a slot 59 in the portion 54 of the slide, and the slot 59 has a straight side and a convex side. The hump or struck-up area 58 engages the convex side of the slot while the straight portions of the lever 57 at the sides and base of the struck-up portion 58 engage the straight side of the slot, thus providing a three-point mechanical contact between the slide and lever 57, which rocks relative to the slide during actuation thereof. The lever 57 has a tongue 60 extending from one of its ends into an opening in the bottom of the trough of a substantially V-shaped saddle 61, which is seated in a recess provided therefor in the wall of the casing part 26 at one end of the chamber 56, serving to fulcrum said end of the lever. The other end of the lever 57 is notched for reception of one end of a substantially U-shaped over-center spring 64, the other end of which is similarly arranged in the notched end of a movable electrical contact arm 65 to mechanically connect the switch and movable electric contact arm for operation in a manner hereinabove described in detail.

The movable electric contact arm comprises a resilient strip of conducting material having one end secured to the casing part 26 within the chamber 56 adjacent one end thereof by screws 66 which also engage with threaded openings in stationary contact plate 35 thus establishing electrical connection between the stationary contact plate 35 and movable contact arm 65. The stationary contact plate 36 at the other end of the casing 25 has an arm 67 arranged along a portion of chamber 56 in front of the switch, and an electric contact point 68 is secured to the inner face of the arm 67 adjacent its end. The movable contact arm has a similar contact point 69 secured to its outer face adjacent its end which is connected to the over-center spring 64 and in alignment with contact point 68. The movable

contact arm 65 is biased to closed circuit position, that is, to normally maintain the contact points 68 and 69 in engagement so that the relay will not interrupt the circuit in which it is connected so long as normal conditions exist in the circuit, but upon creation of abnormal conditions the bimetallic plate 45 will be deflected by the grid 40 and move slide 54 which in turn moves lever 57 from the position of Fig. 6 to the position shown in Fig. 5. This causes shifting movement of the over-center spring 64 to move contact arm 65 and the contact point 69 thereon away from contact point 68, breaking the circuit. If there is nothing, other than the abnormal current conditions which heat the grid and cause deflection of the bimetallic plate which causes opening of the circuit by operation of the switch as described, to prevent closing movement of biased arm 65 the movable contact will automatically be returned to closed circuit position when normal condition in the circuit again prevails and permits cooling of the bimetallic element and return to its original position, as should be obvious. However, there are conditions under which it is desirable to maintain the switch and movable electric contact arm from re-establishing or closing the circuit automatically, and making it necessary to effect reclosing of the circuit by hand operation, and the present invention provides means for making the relay either automatically or hand resettable as desired, which feature will now be described.

The casing parts 26 and 27 have complementary faces which interfit to form a housing for the stationary contact plates 35 and 36, movable contact arm 65, the reset member comprising the movable control plunger 70, and the associated parts on the reset member. The control plunger 70 may also be designated a movable reset control plunger.

The movable contact arm 65, a thin resilient strip of metal, previously described in part, has a curved substantially U-shaped portion 71 intermediate its ends arranged in alignment with the control plunger 70, the said U-shaped portion 71 to accommodate and cooperate with the plunger as will be pointed out in detail hereinafter. The complementary faces of the casing parts 26 and 27 each have corresponding grooves 72 formed therein adjacent their tops to form a chamber 73 when assembled. A coil spring 74 is mounted on the stem of the control plunger 70 and partly compressed between a fixed collar 75 on the control plunger stem and the bottom of chamber 73 to press against the collar and urge the plunger outward. A head 76 is provided on the outer end of the control plunger stem for engagement by a finger of the hand when turning the control plunger to establish it in operative and inoperative positions when making the relay either manually or automatically resettable.

The thermal relay reset actuator mechanism for manually resetting the relays comprises a reset button 77 conveniently provided on the cover 65 10^a on the casing 10 adjacent the push button control station 23 and a spring plate 77^a rigidly connected at or near its bottom edge to the inner face of the front cover 10^a. The plate extends upwardly from its points of attachment to the cover and has a medial portion or section spanning the lower portion of the switch. The front face of said medial section is in position to be engaged by the rear end of the button 77 as clearly shown in Figs. 2 and 3. The spring plate 77^a is generally crescent-shaped with the ends forming

resilient head-engaging arms which extend upward in Fig. 1, the right-hand arm being designated 77^b and the left-hand arm being broken away. The left-hand arm is a mirror image of the illustrated right-hand arm. The spring plate also has depending attaching members to secure it to the cover 10^a. The shape of the spring plate 77^a is such that the portions adjoining the head-engaging arms each have a gradually diminishing width to provide stability, and a certain amount of rigidity, for the arms, the relatively narrow head-engaging arms being more resilient than said portions of the spring plate integral with and immediately adjoining them. The upper end of the head-engaging arm 77^b is directly in front of the corresponding head 76 at the right and the other arm is directly in front of the similar head at the left. When the control plungers 10 are in their forward positions to bring each head 76 into the position shown by dot-and-dash lines in Fig. 3 which is the manually resettable position of said head and plunger, the corresponding arms on the plate 77^a are positioned to engage the heads to move the control plungers inward or rearward. It will be apparent that with the control plungers in their forward, manually resettable positions, they can be moved simultaneously rearward by pressing on the button 77 to flex the spring plate 77^a rearward, the said spring plate through its respective arms engaging and moving the respective control plungers.

The invention is not to be restricted to the inclusion of the reset button 77 since, obviously, the reset button may be removed and the spring plate 77^a actuated by engaging the same with any suitable object inserted through the aperture in the casing cover accommodating the reset button and including, among other objects, the finger of the operator.

It will thus be seen that the cover 10^a on the casing 10 entirely carries all of the thermal relay reset actuator mechanism for operating the control or movable reset control plungers 10 whereby, upon the removal of the cover 10^a, all of the control plunger actuating mechanism will be cleared, as a unit, from the thermal relay units and the respective control plunger of each whereby the head 76 of each control plunger 10 is readily accessible for manipulation to rotate the control plungers to either automatically resettable or manually resettable position. It is to be understood that the cover 10^a may be so mounted on the casing 10 that it may be completely removed therefrom or, as an alternative, the cover 10^a may be hinged to the casing 10 in any suitable manner such as by providing hinges on one side of the casing. It follows that, should the cover 10^a either be completely removed or turned on hinges away from the open face of the casing 10, the control plunger actuating mechanism will be removed from the thermal relay units to render the heads 76 of the control plungers 10 readily accessible for manipulation.

Furthermore, inasmuch as the spring plate 77^a is resilient, and the reset button 77 engages said spring plate intermediate the ends of said plate, pressing the reset button 77 will cause the resilient head-engaging arms 77^b to be brought into resilient engagement with the heads 76 of control plungers 10 and, should the control plungers 10 fail to move inward for any reason, continued pressure on the reset button 77 will not rupture or damage any of the parts since the head-engaging arm 77^b engaging that particular head 76 will yield rather than force the head against the ac-

tion of the obstruction which prevents the movement of the control plunger.

Obviously, inasmuch as the thermal relay units 25 are electrically connected to the electro-magnet of the motor starter, it is not absolutely essential that the thermal relay units be mounted in the same casing as the electro-magnetic motor starter. In Figs. 1 and 2 the thermal relay units have been shown mounted directly on portions of the electro-magnetic motor starter switch but this is primarily done for purposes of compactness and convenience. If found desirable, one or more of the thermal relay units may be mounted in a suitable casing remotely spaced from the electro-magnetic motor starter but connected thereto by suitable electrical connectors. In the latter event, the instant invention comprising the thermal relay reset actuator mechanism may be mounted on the cover of the casing which houses the thermal relay units per se and the function of the thermal relay reset actuator mechanism with respect to the control plungers 10 and the heads 76 thereon will be the same as described in the foregoing. In other words, the presence of the electro-magnetic motor starter switch immediately adjacent the thermal relay units is not necessary in order to have the thermal relay reset actuator mechanism of the present invention function properly.

Each of the relay casing parts 26 and 27 also has a groove 78 between the chambers 73 and 56 which afford, in conjunction with opening 79 at the top of the casing, stabilized guided movement to the control plunger 10, as best shown in Figs. 8 and 9. Below the chamber 56 of the casing, and the U-shaped portion 71 of the contact arm 65, the casing parts 26 and 27 have grooves which provide a socket or chamber 80 in which the lower end of the control plunger is located. Lugs 81 at the top of chamber 80 and at one side thereof are situated to be engaged by the top edge or shoulder of a lug 82 radially projecting from the lower end of the control plunger stem to hold the control plunger in the inoperative position shown in Fig. 7, at which time the movable contact arm 65 is freely movable to open and closed circuit positions relative to the fixed contact 63 in accordance with movements of the bimetallic plate 45, as previously explained.

As shown best in Fig. 8, the bottom of U-shaped portion 71 of the movable contact arm when in closed circuit position is in a plane substantially parallel to but spaced from a plane in which the front wall of socket 80 is located and along which the lug 82 of the control plunger moves when the relay is used as manually resettable. The top edge or shoulder of lug 82 is in engagement with the confronting edge of the contact arm when in closed position, as shown in Figs. 5 and 8. At this time the control plunger spring is exerting force against the collar 75, which is sufficient to maintain the locking engagement between the movable contact arm and shoulder of lug 82, as shown in Fig. 8, so long as the electric circuit remains closed. As soon as the circuit is interrupted, however, the snap-action switch moves the movable contact arm back and clear of the shoulder of the lug 82, at which moment the spring 74 expands and forces the control plunger up in the casing to the position of Fig. 9, where the lug 82 sufficiently overlaps the bottom of U-shaped portion 71 to block circuit closing movement of the movable contact arm. Under the then prevailing conditions, whether normal or abnormal in the circuit, closing of the

circuit cannot be accomplished until the control plunger 70 is sufficiently depressed manually by pressure on its head 76 to move the lug 82 beyond the clear of U-shaped portion 71 of the movable contact arm 65, to permit the arm 65 being moved by the thermal relay switch mechanism to the position of FIG. 8. Obviously, when downward pressure on the control plunger is released the spring 74 urges it upward and it is arrested in its upward movement by engagement of the shoulder of lug 82 against the confronting edge of the movable contact arm portion 71.

Opening or rearward movement of the movable contact arm 65 is limited by stops or lugs 83 located in the chamber 56 of the casing 25 behind said arm, and by similar lugs 84 in the chamber behind the switch lever 57 for abutment thereby. Closing or forward movement of the same parts is limited by engagement of contact points 68 and 69.

It should be apparent from the foregoing that in order to make the relay automatically resettable the control plunger 70 is depressed as far as it can move downward against spring 74 and given a quarter turn to place the lug 82 in locked relation with the lugs 81 in chamber 80 so that only the stem of the control plunger extends across the U-shaped portion 71 of movable contact arm 65 and spring 74 is inactive. The stem of control plunger 70 is then disposed across U-shaped portion 71 but sufficiently clear or spaced therefrom to not interfere with operation of the contact arm 65 in either direction of its circuit making and breaking movements. To make the relay manually resettable the control plunger is given a quarter turn in reverse direction to establish the lug 82 in operative relation with the movable contact arm 65 as previously explained. The head 76 of the control plunger is pointed at one end to conveniently serve as an indicator as to which of its selective positions, operative or inoperative, the control plunger occupies, so that the operator will readily know whether the relay is manually or automatically resettable.

While the thermal relay reset actuator mechanism has been herein described in connection with thermal relay units forming the subject matter of said above mentioned application Ser. No. 373,189, it is to be distinctly understood that said thermal reset actuator mechanism is applicable to any other types of structures with which its use is suitable.

The invention has been illustrated and described in its preferred embodiment and has included certain details but, it should be understood that the invention is not to be limited to the precise details herein illustrated and described since the same may be carried out in other ways, falling within the scope of the invention as claimed.

What I claim is:

1. In combination with an electric switch of the magnetic motor starter type, a casing, a plurality of thermal relay units mounted in said casing and each having a movable reset control member, a movable cover mounted on said casing, a member mounted on and entirely carried by said cover, said member having resilient means thereon adapted to be moved with respect to said cover into substantially simultaneous engagement with said reset control members, and means to urge said member into substantially simultaneous resilient engagement with said reset control members.

- 2. In combination with an electric switch of the magnetic motor starter type, a casing, a plurality of thermal relay units mounted in said casing and each having a movable reset control member, a movable cover mounted on said casing, a resilient member entirely carried by said cover and mounted thereon with one end movable with respect thereto, said resilient member being adapted to resiliently engage said reset control members substantially simultaneously upon actuation of the movable end of said resilient member, and means to urge said resilient member into substantially simultaneous engagement with said reset control members.
- 3. In combination with an electric switch of the magnetic motor starter type, a casing, a plurality of thermal relay units mounted in said casing and each having a movable reset control member, a movable cover mounted on said casing, and a resilient member entirely carried by said cover and having one end fixed thereto with the remainder of said member movable with respect thereto and having a portion terminating in a pair of spaced sections each having gradually diminishing widths toward its outer end which forms an arm adapted to resiliently engage one of said reset control members whereby upon actuation of said resilient member the reset control members of said plurality of thermal relay units are substantially simultaneously engaged and moved to reset position.
- 4. In combination with an electric switch of the magnetic motor starter type, a casing enclosing said switch, a plurality of thermal relay units mounted in said casing and disposed at opposite sides of said switch, said thermal relay units each having a movable reset control member, a movable cover mounted on said casing, and a resilient member entirely carried by said cover and mounted thereon with one end movable with respect thereto, said resilient member having a medial section spanning a portion of said switch and the movable end thereof having a plurality of spaced projecting arms each being adapted to resiliently engage one of said reset control members whereby upon actuation of the movable end of said resilient member the reset control members of said plurality of thermal relay units are substantially simultaneously engaged and moved to reset position.
- 5. In an electric switch construction of the magnetic motor starter type the combination of a casing for said switch, a movable cover mounted on said casing, a thermal relay unit mounted in said casing and including a reset control member adapted to be manipulated manually to move the same to one position to render the thermal relay unit automatically resettable and to another position to render the thermal relay unit manually resettable, and a reset control member operating means adapted to move said reset control member when the same is in manually resettable position to reset said thermal relay unit, said operating means being entirely carried by said movable cover whereby when the latter is moved away from said casing the reset control member is rendered readily accessible for manual manipulation.
- 6. In an electric switch construction of the magnetic motor starter type the combination of a casing for said switch, a movable cover mounted on said casing, a plurality of thermal relay units mounted in said casing and each including a reset control member adapted to be individually manipulated manually to move the same to one

position to render the thermal relay unit automatically resettable and to another position to render the thermal relay unit manually resettable, and a reset control member operating means adapted to substantially simultaneously move said reset control members when the same are in manually resettable position to reset said

plurality of thermal relay units, said operating means being entirely carried by said movable cover whereby when the latter is moved away from said casing said reset control members are rendered readily accessible for said individual manual manipulation.

PAUL M. CHRISTENSEN.

CERTIFICATE OF CORRECTION.

Patent No. 2,329,252.

September 14, 1943.

PAUL M. CHRISTENSEN.

It is hereby certified that error appears in the printed specification of the above numbered patent requiring correction as follows: Page 2, first column, line 32, for "station 2" read --station 23--; and that the said Letters Patent should be read with this correction therein that the same may conform to the record of the case in the Patent Office.

Signed and sealed this 26th day of October, A. D. 1943.

Henry Van Arsdale,

Acting Commissioner of Patents.
